UNITED STATES PATENT OFFICE.

JAMES N. HEALD, OF WORCESTER, MASSACHUSETTS, AND WILLIAM LAW, OF HARTFORD, CONNECTICUT, ASSIGNEES TO THE HEALD MACHINE COMPANY, OF WORCESTER, MASSACHUSETTS, A CORPORATION OF MASSACHUSETTS.

GRINDING MACHINE.

Application filed January 30, 1926. Serial No. 34,881.

The present invention relates to grinding machines of the type employed for surface grinding, and more especially wherein the faces of successive small flat articles, such as piston rings and the like, are subjected to the action of a grinding wheel.

In previous machines of this type, as exemplified, for instance, by United States Letters Patent to Littman, No. 1,361,883, dated December 14, 1920, and by the co-pending application of William Law, Serial No. 681,163, filed December 17, 1923, now Patent No. 1,582,481, each workpiece, upon its arrival in grinding position, has rotation imparted thereto so as to subject the entire area of the plane face or surface to be ground to the action of the rotating grinding wheel,—the latter having its axis substantially at right angles to the axis of rotation of the workpiece, and being mounted for sliding movement longitudinally of its axis, so as to carry the periphery of said wheel into and out of contact with the surface to be ground.

In such a machine, as the grinding wheel and the workpiece are brought together, the initial contact is between the outer edge or corner of the workpiece and the corner of the grinding wheel, a condition which leads to excessive wear and attrition of said wheel, especially where the cut to be taken is a heavy one, inasmuch as in this initial contact the wheel, at the very beginning, reaches its maximum depth of cut.

The present invention has for its primary object the elimination of the above mentioned difficulties in grinding machines of the surface type, whereby the grinding wheel may be brought into contact with the workpiece without shock, regardless of the depth of cut to be taken, and wherein excessive sparking and chipping and wear of the face or corner of the grinding wheel is effectually avoided. Other and further objects of the invention will be made apparent in the following detailed description, reference being had in connection therewith to the accompanying drawings, wherein—

Fig. 1 is a view in side elevation of a grinding machine embodying the invention.

Fig. 2 is a top plan view of said machine.

Fig. 3 is a longitudinal sectional view, on an enlarged scale, of the wheel-carrying devices of said machine.

Fig. 4 is a top plan view of certain of the parts shown in Fig. 3.

Fig. 5 is a fragmentary detailed view, on an enlarged scale, showing in front elevation the construction at the right hand end of Fig. 4.

Fig. 6 is a transverse sectional view, certain parts being shown in end elevation, as viewed from the line 6 of Fig. 3.

Fig. 7 is a view similar to Fig. 6, showing parts of the machine as viewed from its right hand end.

Fig. 8 is a diagrammatic view illustrative of the approach of the grinding wheel toward the work, in the operation of the machine.

Fig. 9 is a face view of a cam employed in the machine.

Like reference characters refer to like parts in the different figures.

Referring to Figs. 1 and 2, the machine provides the usual base 1, the latter having suitable slideways 2 and 3, Fig. 7, for the longitudinal reciprocation of a wheel head or carriage 4. The latter, in the manner to be hereinafter particularly described, carries a rotating grinding wheel 5, which operates on the faces of workpieces that are successively disposed in grinding positions beneath said wheel; as herein shown, said workpieces, in the form, for instance, of rings *a*, *a*, are loaded or stacked vertically in a magazine 6, beneath which rotates intermittently an apertured carrier plate 7. Each movement of said plate 7 brings one of its apertures 8 directly below and in concentric relation to the stack of rings *a*, *a*, at which time the lowermost ring *a* drops into the aperture 8 and rests against the stationary supporting surface below the plate 7. On the ensuing movement of plate 7, this ring *a* is carried along with said plate, but the superposed rings of the stack are prevented from so moving by the confining action of the magazine 6, as will be well understood. The construction and operation of these work feeding instrumentalities of the machine form no part of the present invention, and hence a detailed description thereof is unnecessary, since such instrumentalities are well known in the art, being shown in the aforesaid patent to Littman, and also in the patent to James N. Heald, No. 1,486,580, dated March 11, 1924. It is sufficient to note that each

ring α , as removed from the bottom of the stack by the plate 7, is deposited by said plate upon a rotating magnetic chuck 9, whereupon said ring α , rotating with said chuck, has its face ground by the wheel 5, as hereinafter described; then, by a further movement of plate 7, the ground ring α is moved away from grinding position and simultaneously an unground ring takes its place on the chuck 9.

The wheel head or carriage 4 reciprocates longitudinally on the slideways 2 and 3, this motion being imparted in any well known manner, as by the connection of said head 4, through a rod 10, Fig. 3, to a double acting piston 11, the latter being contained in a fluid pressure cylinder 12 and being actuated by the admission of fluid under pressure to one end or the other of said cylinder. Any suitable reversing valve, not shown, may be employed to control the direction of flow of the pressure fluid, said valve being made responsive to the movements of a swinging member 13, Fig. 1, which is acted upon alternately by a pair of longitudinally adjustable dogs or stops 14, 14, carried by the head 4. As will be well understood, the reciprocatory travel of the head 4 is determined by the adjustment and spacing of the dogs 14, 14: such reciprocation, while here shown as effected by hydraulic means, may obviously be effected by any other means well known in the art. According to the present invention, this longitudinal reciprocation of head 4 is not employed, as in previous machines of this type, to move the grinding wheel 5 into and out of contact with the surface being ground, but on the contrary, is simply employed to give a traversing action of the grinding wheel across the surface being ground, after the grinding contact, as hereinafter described, has been made, thereby to produce a more finely finished surface, free of "grinding lines." In reality, this longitudinal reciprocation of the head 4 may be dispensed with, without affecting the attainment of the present invention, the latter, as will now be shown, involving a novel departure from established practices in the manner of obtaining the movement of the grinding wheel 5 into contact with the surface of the rotating ring or workpiece α .

As shown in Fig. 3, the grinding wheel 5 is suitably mounted on a spindle 15, the latter being journaled in bearings 16 and 17 provided by a longitudinally disposed member 18. The spindle 15 has fastened to it a long drum 15^a and by means of a belt 15^b and a driving pulley, not shown, said drum 15^a and spindle are rotated. At its inner end, said spindle 15 provides a pulley 19, which, by means of a belt 20, Fig. 6, drives a suitable pulley 21, which is mounted on a shaft 22. The member 18, as shown at 23, Fig. 3, provides an opening for the passage of belt

20, and said member 18 on its opposite side portions has flanges 24, 24, whose plane under surfaces have a gradual downward inclination with reference to the axis of spindle 15. These flanges 24, 24 work in similarly inclined slideways 25, 25 provided by the head 4, and provision is made for causing relative movement between member 18 and the head 4 supporting it, in the following manner:—

As shown in Figs. 3 and 4, the head 4 has suitably journaled therein a transverse shaft 26, the latter carrying a worm wheel 27 which is in mesh with a worm 28 on a shaft 29, journaled in the head 4 at right angles to and below the shaft 26. The shaft 29 receives its rotation, at considerably reduced speed, from a pulley 30, the latter being secured to a sleeve 31 which is loosely journaled on shaft 29. The pulley 30 is driven by a belt 32, Fig. 7, from a pulley 33 on shaft 22, and the rotation of sleeve 31 is imparted to shaft 29 through the medium of change speed reduction gearing embodying a gear 34 on sleeve 31 in mesh with a gear 35 on a countershaft 36, the latter providing a gear 37 in mesh with a gear 38 on shaft 29. Through this reduction gearing and also through the reduction afforded by the worm drive 27, 28, the shaft 26 is caused to rotate at a very slow speed,—one revolution of said shaft 26 corresponding approximately to the time consumed by a single cycle of operations of the machine, namely the grinding of a single workpiece and its removal from grinding position, accompanied by the movement of an unground workpiece into grinding position.

Secured to the shaft 26 is a cam 39 which is of the shape shown in Fig. 9, having a raised portion 40, from which the descent is extremely gradual for almost the entire periphery of the cam. A roller 41 is carried by the rear end of member 18, in position to make contact with said cam, and a spring 42, Figs. 3 and 4, bearing against a portion 43 of member 18, is effective to thrust said member 18 to the left, relatively to the head 4, thus to press the roller 41 toward the cam 39.

Thus during each revolution of cam 39, the member 18, carrying the grinding wheel 5, feeds gradually downwardly and to the left for nearly the entire revolution of said cam, and then as the portion 40 of cam 39 becomes effective, said member 18 moves quickly upwardly and to the right,—the vertical component of the motion being relatively slight, due to the gradual inclination of the ways 25, 25. This upward right hand motion carries the grinding wheel 5 out of contact with the workpiece, and during the engagement of cam portion 40 with roller 41, the finished workpiece is removed from the chuck 9 by a movement of plate 7, and

a new unground workpiece is deposited on said chuck in grinding position; this action of plate 7 may be effected in any well known manner, as for instance, by a cam 44, Fig.

- 5 1, on the front end of shaft 6, which at the proper time, actuates a bell crank lever 45, the latter by its movement adapted to secure a single revolution of an actuating member 46, Fig. 2, whereby, through rod 47, 10 a single step in the intermittent rotation of plate 7 takes place. Then, following the high portion 40 of cam 39, comes the gradually descending portion for the remainder of its periphery, by means of which the member 18, under the influence of spring 42, feeds gradually to the left and downwardly this motion being partaken of by the grinding wheel 5 and causing the initial contact with the workpiece to be effected by the 15 wheel's periphery, as shown in Fig. 8, instead of by the corner of the wheel, as in previous machines of this type. This gradual downward feed brings the wheel and the workpiece into full surface contact as soon 20 as any contact whatsoever is made, and from then on the downward feed is gradual until the desired depth of cut is reached. This effectually eliminates the excessive 25 sparking and the chipping and attrition of the wheel which takes place when the feed, as in previous machines of this type, is from the side of the workpiece. The depth of cut taken by the wheel in the present 30 machine can be regulated very closely by the provision of a threaded adjustable stop member carried by a projection 49 of member 18, and adapted to engage a fixed lug 50 projecting from the head 4, as shown 35 in Fig. 5. When the left hand downward 40 movement of member 18, under the influence of spring 42, has proceeded far enough to bring member 48 against lug 50, the feed of the wheel 5 toward the work thereupon ceases, even though the roller 41 may not 45 at such time be bearing against the gradually descending portion of cam 39. The adjustment member 48 thus affords an exceedingly delicate means for determining the 50 depth of cut of the wheel. Compensation may be made from time to time for wear of the wheel in continued use, by raising the magnetic chuck 9, through the medium of the usual hand wheel 51.

We claim:

- 55 1. In a grinding machine, means for imparting rotation to substantially flat work-pieces, a grinding wheel having its axis of rotation substantially at right angles to the axis of work-piece rotation, and means for feeding said wheel into grinding position by movement in a line contained in the angle between said two axes.
- 60 2. In a grinding machine, a rotating grinding wheel, means for reciprocating said wheel in a path parallel to its axis of rota-

tion, and means for feeding said wheel into contact with the work surface to be ground, by movement in a direction inclined from the axis of rotation of said wheel.

3. In a grinding machine, a rotating grinding wheel for operation on the plane faces of work-pieces, said wheel, in the intervals between successive work-pieces, being laterally displaced from grinding position, means for reciprocating said wheel in a path parallel to its axis of rotation, and means for feeding said wheel into grinding position by a movement which brings at once the full width of the periphery of said wheel into contact with the plane surface to be ground.

4. In a grinding machine, means for imparting rotation to substantially flat work-pieces, a grinding wheel having its axis of rotation substantially at right angles to the axis of workpiece rotation, means for reciprocating said wheel in a path parallel to its axis of rotation, and means for feeding said wheel into grinding position by movement in a line contained in the angle between said two axes.

5. In a grinding machine, a rotating grinding wheel, means for successively disposing substantially flat workpieces in grinding position, means for imparting rotation to the workpieces so disposed, and means operating in timed relation to the disposal of successive workpieces in grinding position, for moving said wheel into grinding position, said wheel movement being in a direction inclined from the axis of rotation of said wheel.

6. In a grinding machine, the combination with a reciprocating grinding wheel carriage, and means to reciprocate it of a grinding wheel support mounted on said carriage for longitudinal movement in a direction inclined from the direction of carriage movement, means for moving successive work-pieces into and out of grinding position and means for moving said support in timed relation to the movements of successive work-pieces into and out of grinding position.

7. In a grinding machine, the combination with a reciprocating grinding wheel carriage, and means to reciprocate it of a grinding wheel support mounted on said carriage for longitudinal movement in a direction inclined from the direction of carriage movement, means for moving successive work-pieces into and out of grinding position, and means for moving said support in timed relation to the movements of successive work-pieces into and out of grinding position, said means including a cam by which the grinding wheel is withdrawn from grinding position, and a spring by which said wheel is fed into grinding position.

8. In a grinding machine, the combination with a rotatable chuck adapted to hold work-

pieces with flat surfaces perpendicular to the axis of rotation of said chuck, and a grinding wheel whose cutting face has elements parallel to the surfaces of said workpieces when held by said chuck, of means for feeding said grinding wheel into grinding contact with the workpieces at an acute angle to their flat surfaces.

9. In a grinding machine, the combination with a rotatable chuck adapted to hold workpieces with flat surfaces perpendicular to the axis of rotation of said chuck, a grinding wheel whose cutting face has elements parallel to the surfaces of said workpieces when held by said chuck, and means to reciprocate said grinding wheel in a path parallel to the surfaces of said workpieces, of means for feeding said grinding wheel into grinding contact with the workpieces at an acute angle to their flat surfaces.

10. In a grinding machine, the combination with a rotatable chuck adapted to hold workpieces with flat surfaces perpendicular to the axis of rotation of said chuck, a grinding wheel whose axis of rotation is perpendicular to the axis of rotation of said chuck and means to reciprocate said grinding wheel in a line parallel to its axis, of means for feeding said grinding wheel into grinding contact with the workpieces at an acute angle to the axis of said wheel.

11. In a grinding machine, means for intermittently and successively moving workpieces having a flat surface into grinding position, means for rotating said workpieces at said position with their flat surfaces perpendicular to the axis of rotation, a grinding

wheel having its axis of rotation substantially at right angles to the axis of workpiece rotation, means for reciprocating said wheel in a path parallel to its axis of rotation, and means for feeding said wheel into grinding position by movement in a line contained in the angle between said two axes.

12. In a grinding machine, means for moving successive workpieces into and out of a grinding position, means for rotating the workpieces when at said position, a grinding wheel, means for rotating said wheel, a movable support for said wheel by which to carry it into and out of grinding position by movement in a direction at an acute angle to its axis of rotation, and means for moving said support in timed relation to the movement of the said successive workpieces into and out of grinding position.

13. In a grinding machine, a base, slideways provided by said base, a grinding carriage supported for movement on said slideways, means to reciprocate said carriage on said ways, a second set of slideways on said carriage located in a plane which bears an acute angle to the plane of the first named slideways, a second carriage mounted for movement on said second slideways, means for reciprocating said second carriage, a grinding wheel, a spindle upon which said grinding wheel is mounted, and supports for said spindle in said second carriage whereby its axis is parallel to the plane of the first named slideways.

JAMES N. HEALD.
